UNITED STATES PATENT OFFICE

GARRISON BABCOCK, OF SEATTLE, WASHINGTON, ASSIGNOR TO AMERICAN TELECHRONOMETER COMPANY, OF SEATTLE, WASHINGTON, A CORPORATION OF WASHINGTON

TELECHRONOMETER

Original application filed October 15, 1921, Serial No. 508,087. Patent No. 1,747,210, dated February 18, 1930. Divided and this application filed April 6, 1929. Serial No. 352,983.

This invention relates to telechronometers, more particularly to a new and improved telechronometer for use on a telephone line.

In my copending application, Serial No. 5 508,087, filed October 15, 1921, Patent No. 1,747,210, Feb. 18, 1930, of which application this case is a division, I disclose a telechronometer and a telephone system employing that telechronometer. For the full 10 operating details of such a system, reference is here made to the above copending application.

Briefly, however, the telechronometer comprises an electromagnetic meter located 15 at the subscriber's premises and operated by reversals of current over the subscriber's line to the telephone office at periodic intervals during the conversations over the telephone.

The telephone comprises the usual talking instrumentalities and may be either a manual telephone or an automatic telephone depending upon the system with which it is used.

The telechronometer itself, which is disclosed in detail in the above mentioned copending application, comprises a plurality of dials over which creep register indicators which are driven by a ratchet and gear arrangement actuated electro-magnetically by 25 the reversal of the polarity of current flowing over the telephone line.

To bring about this reversal of current, a reversing switch or pole changer is located in the central office and associated 30 with the battery feed leads of the cord circuit, in a manual exchange or of the line relay of the connector or final selector switch of an automatic telephone exchange.

Briefly, this pole changer comprises a 35 plurality of resistance units, preferably four in number, which are operated in pairs to periodically reverse the polarity of the battery connection to the answering supervisory relay of the cord circuit. The battery feed 45 for the transmitter of the calling station is drawn through this relay as will be well understood by those skilled in the art. The resistance units are of the type which vary responsive to the change of pressure upon 50 them and might conveniently be carbon pile

resistors. When the pressure on the pile is increased the resistance decreases and the current flow correspondingly increases. The driving arrangement for the plungers which alternately compress and decompress the 55 resistance piles is arranged so that while one of the pairs of resistances is being compressed the other one is being decompressed in the same ratio. The battery supply leads of the line relays are connected to both of 60 these rheostats so that the change in resistance values of the two pairs of resistances effects a change in polarity of the connection in the manner explained in detail in my above mentioned copending application. 65

Inasmuch as the registering mechanism is located at the subscriber's premises, it is desirable that the meter be sealed and protected to prevent unscrupulous subscribers from disabling it to thereby reduce their 70 telephone bills.

The sealing of the meter has been employed heretofore to prevent tampering with this mechanism, and while that seal is effective for that purpose, it does not guard 75 against the contingency of the subscriber short-circuiting or grounding the electro-magnets of the meter to thereby prevent its operation.

In telechronometers devised heretofore the 80 electro-magnets of the meter were in the line circuit only during conversation and then in such a manner that the detection of a short circuit or a ground connection by tests supplied at the central office was very 85 difficult.

In my present invention which is based upon the disclosure of the above copending application, I have provided a new and improved electro-magnetic circuit for the telechronometer, which circuit lends itself to the ready detection of circuit tampering by the subscriber to prevent the operation of the telechronometer. 90

The electro-magnet of the telechronometer 95 comprises two windings which are serially connected in the line circuit. The windings are so designed that when the normal line circuit current is flowing through either one of them, the meter will be operated. That 100

is, each of these two windings is made sufficiently strong electro-magnetically so that it is capable of operating the meter without the assistance of the other winding. The 5 two windings have identically the same impedance, with the result that the line circuit to the telephone office is balanced electrically.

If the subscriber short circuits one of the 10 windings of the meter, the electrical circuit is unbalanced, and the detection of that short circuit is made readily possible by the reduced resistance and inductance of the line circuit. The short circuiting of the one 15 winding will not prevent the operation of the meter since the remaining winding is of sufficient strength to fully operate the telechronometer unaided.

If the subscriber short circuits both of the 20 windings of the meter, of course it cannot be operated but the reduction of the impedance of the telephone circuit caused by this short circuit increases the current supplied to the circuit and thereby makes the 25 detection of the short circuit readily possible by the use of the usual and well known testing instrument at the command of the wire chief at the central office.

In the drawing I have indicated by the 30 usual circuit symbols sufficient apparatus to enable a clear understanding of the invention.

The subscriber's station A is equipped with the usual talking instrumentalities 35 comprising the transmitter X, the induction coil I, the receiver R and the hook switch 4, together with the signal bells 3 and the telechronometer T. The mechanical construction of the telechronometer can best be 40 understood from a reading of the above mentioned copending application to which reference is here made for those details. The electro-magnet of the telechronometer T comprises windings 5 and 6, the winding 5 45 being included in one side of the line to the central office and the winding 6 in the opposite side.

This telephone line terminates at the central office in the line relay LR and in the 50 answering jacks AJ and the calling jacks CJ, not shown, as is the custom in a common battery telephone system.

Responsive to the removal of the receiver R from the hook switch 4 a circuit is completed from ground through the outer break springs on the relay COR, through the line conductor 1 and the winding 6 of the telechronometer T, through the transmitter X, the primary winding of the induction 55 coil I, through the winding 5 of the telechronometer, through the make contacts of hook switch 4, through the line conductor 2, through the inner break contacts of the cut-off relay, through the winding of the 60 line relay to battery. The line relay ener-

gizes over this circuit and closes the obvious circuit for the line lamp LL to indicate to the operator that the station A has initiated a call.

The operator picks up the answering plug 70 AP of the cord circuit CC and inserts it into the answering jack AJ associated with the line A, thereby completing a circuit from grounded battery through the sleeve relay SR through the sleeve of the plug and 75 jack AP and AJ through the winding of the cut-off relay COR to ground.

The cut-off relay energizes over this circuit and opens the circuit of the line relay LR to permit that relay to fall back and extinguish the line lamp LL and to clear the line A of ground and battery connections. As is well understood by those versed in the telephone art, the central office battery has 80 one of its poles permanently connected to 85 the ground.

When the connection has been so established, the transmitter of the sub-station A will be supplied with battery over a circuit 90 extending from the negative pole of battery through the resistors R1 and R3 in parallel to the lower and upper terminals respectively of the relay AS, and from the positive terminal of battery which is also connected to ground, through resistance units 95 R2 and R4 in parallel to the opposite terminals respectively of the answering supervisory relay AS.

Since the resistance unit R4 is at its maximum resistance value when the resistance unit R2 is at its minimum value, the connection through one of these resistors to one of the terminals of the relay AS will, in effect, be nullified. Assume for the moment that the resistance R4 is the high resistance unit, the transmitter current then traverses the circuit through resistance R2 through the upper winding of the supervising relay AS to the tip connection of the plug AP and the jack AJ over the line conductor 1 through the upper winding 6 of the telechronometer T, through the transmitter X, through the primary winding of the induction coil I, through the lower winding 5 of the telechronometer, through hook switch 5 spring 4 and its make contact, through the line conductor 2 to the ring connection of the jack AJ and the plug AP, through the lower winding of the relay AS, through the resistance R1, through the ammeter A, to the negative pole of battery. It will be remembered that resistances R1 and R2 are operated as a pair so that when R2 is low in value R1 will be correspondingly low in value.

The operator then throws the listening key LK to connect her head set into the circuit, over which she can converse with the subscriber at station A to ascertain what number he is calling.

Assuming that the desired party is the station B, the operator picks up the calling plug CP and inserts it in the calling jack CJ associated with that line. By operating the ringing key RK the subscriber B is signalled in the usual manner and answers his telephone by removing the receiver from the switch hook.

The transmitter of the telephone B receives current over a circuit from positive battery through the lower winding of the calling supervisory relay CS, through the normally closed contacts of the ringing key RK, through the ring conductor of the plug CP and jack CJ, through the line conductor 2 of the line B, through the hook switch, telechronometer winding, induction coil, transmitter, and second telechronometer winding of the telephone sub-station B, line conductor 1 leading therefrom, the tip conductor of the jack CJ and plug CP, the upper normally closed contacts of the ringing key RK, through the upper winding of the calling supervisory relay CS, through the ammeter A to negative battery. It will be noted that this connection does not include the resistance units R1-R4 inclusive, and therefore that the battery supply current to the transmitter of the sub-station B will not be reversed periodically.

The cord circuit CC will contain other relays, lamps, keys, etc., as is customary with modern telephone cord circuits, but since these instrumentalities do not come within the scope of the present invention, they have been omitted from the drawing to avoid an unnecessary complication thereof.

The parties A and B may now converse over the circuit just traced.

The plungers 79 and 80 of the pole changer associated with the cord circuit CC are operated by the cylinders 73 and 74 in the manner pointed out in detail in the above mentioned copending application. The plunger 79 is withdrawn from the resistance units R1 and R2 while the plunger 80 is pressed against the units R3 and R4 and vice versa.

This reversal of current at the cord circuit CC operates the telechronometer T through the windings 4 and 5 to register a charge against the calling subscriber A indicative of the length of time that the telephone has been in use on the dials of the telechronometer. If the conversation continues, plungers 79 and 80 are re-operated in the reverse direction so that battery supply current is again reversed to the transmitter X through the resistances R1 and R2, and the telechronometer is again operated to assess another charge against the subscriber in the manner pointed out in detail in the copending application referred to above.

If the subscriber attempts to secure his

telephone service without having his telechronometer T register the proper number of units therefor, he might endeavor to apply short-circuit to the winding 5 or to the winding 6 of his telechronometer. The surreptitious application of such a short circuit, if it be to one of the windings, will not however accomplish the purpose that the subscriber intended since each of the windings is sufficiently strong electro-magnetically to be capable of operating the telechronometer properly without the assistance of the other winding.

In the circuit previously traced for the battery feed to the transmitter X at station A, resistances R1 and R2 were assumed to be of low value, and therefore relay AS had negative potential impressed on its lower winding and positive potential on its upper winding. In this case plunger 79 is pressing against R1 and R2 and plunger 80 is retracted from R3 and R4.

After a predetermined time has elapsed, the positions of plungers 79 and 80 are reversed by an operation of cylinders 73 and 74. As explained in my above mentioned copending application, this reversal takes place rapidly. After this reversal resistances R1 and R2 have high value and R3 and R4 low value, the lower winding of AS has positive potential impressed upon it, and the upper winding has negative potential upon it, which it will be noted is the reverse of the initial potentials traced above.

The wire chief could readily ascertain if the winding was short-circuited by inserting a resistance meter in the circuit to the sub-station A, thereby measuring the loop resistance, it would be lowered by the short circuit of the winding. If the two windings were short-circuited there would be an appreciable reduction in the loop resistances and that fact would be readily ascertainable by the corresponding increase in the transmitter supply current had over the line circuit to the transmitter X.

If the subscriber at Station A attempts to disable the telechronometer T by grounding one or the other side of the line, the presence of this ground is readily detected since normally the two sides of the line are balanced and free from ground. The application of ground to one or other side of the line would destroy the normal balance and could be readily picked up by the usual volt meter test devices well known and understood by those skilled in the art.

Having thus complied to the statutes and shown and described a preferred embodiment of my invention, what I consider new and desire to have protected by Letters Patent is pointed out in the appended claims.

What is claimed is:

1. In combination, a telephone station having a pair of line wires, adapted to lead to

- central, an electro-magnetic device at said station; said electro-magnetic device including a pair of coils connected serially each in a limb of the telephone line and a permanent magnet adapted to be actuated by said coils.
2. In combination, a telephone station having a pair of line wires adapted to lead to central, an electro-magnetic device at said station, said device including a magnet and a pair of coils connected serially each in a limb of the line and acting cumulatively to actuate the magnet in accordance with the polarity impressed upon the line.
3. In combination, a telephone line having a pair of metallic conductors, an electro-magnetic device including a pair of actuating coils each connected serially in one conductor of said pair and adapted for energization together, and a permanent magnet adapted to be actuated by said coils.
4. In a telephone system, the combination of a subscriber's station comprising the usual talking instrumentalities connected to a central office by a pair of line conductors, and a meter having two electrically independent and equal windings, one of which is connected in serial relation with each of said line conductors.
5. In a telephone system, the combination of a subscriber's station comprising the usual talking instrumentalities connected to a central office by a pair of line conductors, and a meter having two mechanically and electrically independent windings of identical electric characteristics, one of said windings being connected in serial relation with each of said conductors, and a mechanism operated responsive to an energization of said windings.
6. In a telephone system, the combination of a subscriber's station comprising the usual talking instrumentalities connected to a central office by a pair of line conductors, two mechanically and electrically independent windings of identical electric characteristics, one of said windings being connected in serial relation with each of said conductors, and a mechanism operated responsive to an energization of said windings by electromagnetism set up in said windings.
7. In a telephone system, the combination of a subscriber's station comprising the usual talking instrumentalities connected to a central office over an ungrounded two conductor circuit, and a meter having two electrically balanced windings, one connected in each of said conductors at said station.
8. A method of preventing fraudulent operation of a telechronometer which comprises providing two equal windings for the telechronometer each of which is electro-magnetically capable of operating the instrument, and connecting said windings in serial relation to the two sides of the subscriber's
- line thereby rendering short-circuiting of the telechronometer readily detectable.
- In witness whereof, I hereunto subscribe my name this 25th day of March, 1929.
- GARRISON BABCOCK.
